(57) **CLAIM**

The ornamental design for a tray for toy beads as shown and described.

DESCRIPTION

FIG. 1 is a perspective view of a tray for toy beads showing my new design;

FIG. 2 is a front view thereof;

FIG. 3 is a rear view thereof;

FIG. 4 is a top view thereof;

FIG. 5 is a bottom view thereof;

FIG. 6 is a right side view thereof;

FIG. 7 is a left side view thereof;

FIG. 8 is an enlarged view of portion 8 in FIG. 1; and, FIG. 9 is an enlarged view of portion 9 in FIG. 2. The dash-dash broken lines depict portions of the tray for toy beads that form no part of the claimed design. The dash-dot broken lines depict enlargement cross section boundary lines that form no part of the claimed design.

1 Claim, 9 Drawing Sheets
